CLAIM

We claim an ornamental design for a canister, as shown and described.

DESCRIPTION

FIG. 1 is a front/top perspective view of a canister; FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The evenly-dashed broken lines in the drawings illustrate the portions of the canister that form no part of the claimed design. The dash-dot broken lines in the drawings define the bounds of the claimed design and form no part thereof.
